UNITED STATES PATENT OFFICE.

WILLIAM G. LUTTINGER, OF MORENCI, ARIZONA.

DESIGN FOR A CARBID-LAMP CLEANER.

55,290.

Specification for Design.

Patented May 25, 1920.

Application filed December 3, 1919. Serial No. 342,272. Term of patent 7 years.

To all whom it may concern:

Be it known that I, WILLIAM G. LUTTINGER, a citizen of the United States, residing at Morenci, in the county of Greenlee and State of Arizona, have invented a new, original, and ornamental Design for a Carbide-Lamp Cleaner, of which the following is a specification, reference being had to the accompanying drawing, forming part thereof.

The figure is a perspective view of a carbide lamp cleaner embodying my design.

I claim:

The ornamental design for a carbide lamp cleaner, as shown.

WM. G. LUTTINGER.

Witness:

W. H. ROWE.
